AUTOMATIC PLUG

Application filed December 8, 1924. Serial No. 754,476.

My invention relates to connectors particularly adapted for use in telephone or radio plugs, but not limited to such use.

It is desirable in plugs of this character to provide readily detachable and connectible terminals so that the plug may be readily attached to a cord and with equal facility detached therefrom. Also it is often desirable to connect two circuits, for example, two head sets to a common plug.

According to my invention, I provide a terminal which has suitable clutch means for readily and automatically gripping pin tips or terminals, or other conductors. In the preferred form of my invention, which I have shown herein, provision is made for gripping two sets of terminals so that two receivers may be connected to the same plug.

The clutch for obvious reasons employs a metallic spring which may be depended upon for electrical contact. A metallic seat is therefore not necessary, but is preferable in practice.

In addition, I provide a common release element for releasing the clutch to free all the terminals at once. I also provide automatic expulsion means which may optionally be employed to expel the terminals when they are unclutched.

The clutch element includes a spring which is set at an angle to the socket, so that the tip or pin may be forced past the end of the spring when the pin is inserted, but the pin is thereby caught and can be withdrawn only by bending the spring away from the pin.

For a two cord plug, I provide on each element or contact of the plug a unitary plate with the opposite edges thereof bent about to form opposing sockets or seats, these sockets or seats preventing the lateral escape of the pins or conductors, and between these opposed seats I provide an arched leaf spring, the central part of which is attached to the plate between the seats. A piece of insulation with spaced legs, is mounted above the spring with the ends of the legs in position to press down the ends of the springs, so as to release the tips. If desired, springs may be provided in the seat below the position of the clutching

springs to expel the tips as soon as they are released.

Now, while I have shown the clutch mechanism as applied to the terminals of a plug, it is to be understood that my invention is not limited to use in plugs, but may be employed wherever a quick attachable and detachable connection is desired. The invention is applicable to quick detachable terminals for circuits of every description.

Now, in order to acquaint those skilled in the art with the manner of constructing and operating a device embodying my invention, I shall describe in connection with the accompanying drawings, a specific embodiment of the same.

In the drawings:—

Fig. 1 is a top plan view of a plug embodying my invention;

Fig. 2 is a side elevational view of the same;

Fig. 3 is a central longitudinal section on an enlarged scale taken on the line 3—3 of Fig. 1;

Fig. 4 is a transverse section on an enlarged scale taken on the line 4—4 of Fig. 1;

Fig. 5 is a transverse section taken on the line 5—5 of Fig. 3;

Fig. 6 is a side elevational view with half of the housing or shell removed showing a modification;

Fig. 7 is a transverse section taken on the line 7—7 of Fig. 6;

Fig. 8 is a cross sectional view showing a modification;

Fig. 9 is a fragmentary section taken on the line 9—9 of Fig. 8;

Fig. 10 is a longitudinal cross section showing a further modification; and

Fig. 11 is a fragmentary sectional view illustrating a modification of the device shown in Fig. 10.

Referring now to the device shown in Figs. 1 to 5, inclusive, the plug comprises the usual sleeve contact 1 and tip contact 2 insulated from each other by the insulating washer 3 and held together by the central needle 4, which needle is insulated from the sleeve 1 by an inner sleeve of insulation 5. At its upper end, the sleeve 1 is threaded into a lug or ear 6 formed on the lower end of a plate 7. The

95

100

ear 6 is bent at substantially right angles to the main body of the plate 7, and the upper end of the metallic sleeve contact 1 is preferably threaded into said lug or ear. The 5 needle 4 is, in reality, an elongated bolt of small diameter and at its upper end it extends through a lug 8 bent at substantially right angles from the main body of a plate 9. The needle 4 has at its upper end the head 10 which clamps the lug or ear 8 down upon an insulating washer 11 which separates the ear 8 from the ear 6. The tip 2 is threaded internally and forms a nut which is drawn up on the threaded end of the needle 4 to hold 15 the parts together. The end of the needle may then be soldered to the tip 2 when the parts have been thus assembled. The plates 7 and 9 are preferably formed of sheet metal and they lie substantially parallel to each 20 other. These plates are connected together mechanically by a spacing collar 12 of insulation, which collar has a reduced neck at each end fitting into an aperture in the plates 7 and 9, so as to hold the collar in place. The 25 plates in the upper end of the sleeve contact 1 are surrounded by a housing 13, which is formed of two complementary halves or shells 14 and 15, these shells 14 and 15 having registering apertures in line with the hole 30 through the insulating collar or spacer 12, so that a bolt 16 may pass therethrough and hold the parts together. The holes in the shells 14 and 15 are preferably counterbored to receive the head 17 of the bolt 16 and to 35 receive a nut 18 at the opposite end of said bolt 16. In this manner, the two shells may be made from the same mold.

The plates 7 and 9 each have laterally extending wings, the edges of which are bent 40 into substantially semi-cylindrical form, as indicated at 20, to form seats for the pin terminals or tips 21 which are adapted to enter the same endwise. The purpose of thus bending the edges of the plates 7 and 9 is to 45 restrain the lateral movement of said tips or conductors 21, so that they may be properly gripped by the clutch springs which will now be described. At the upper end of the plate 7, and likewise at the upper end of the plate 9, there is formed an extending ear 50 22 which is bent at substantially right angles to the main body of the plate, so that the two ears 22 extend toward each other. To the bottom of each one of these ears is connected 55 an arched spring 23, as by means of the rivet 24. The ends of the springs 23 extend diagonally toward the seat 20 and project sufficiently far into said seat that it is necessary 60 for the tips 21 to push the end of the spring down in order to push past the same. The spring 23 presses against the tips 21, and due to its diagonal position this spring tends to wedge or strut itself against the tip 21 so as to clutch the same effectually 65 against removal. While I have shown the

spring 23 as having its ends extending into the socket and secured at its middle, it is to be understood that the spring need not serve two sockets, but it is highly advantageous and saving of material to have it do so. Also, 70 instead of having the spring secured by a rivet and an overhanging ear on the plate, I may punch out a pair of ears or lugs 25 and pinch them upon a spring 26, shown in Figs. 8 and 9, such spring having a central 75 loop 27 to provide a narrow neck 28 substantially at right angles to the main body of the spring 26 for conveniently fastening the same into place.

The shell or housing 13 is provided with 80 guiding openings 30, each in line with the corresponding seat 20, so as to guide the tips 21 into place in said seat 20 to be clutched by the springs 23. These guiding openings 30 are formed in the insulating material, of which the shell 13 is composed. The openings serve to limit the lateral play of the tips so that sidewise movement of the same is prevented and the spring 23 cannot be accidentally released by lateral movement of the pins 21 or 85 the conductor cords 31 fastened thereto.

I provide a common release member 32 which has a thumb piece 33 extending above the top of the shell 13. This release member 32 has shoulders 34 formed to engage cooperating shoulders on the housing 13 so as to prevent movement of the release member 32 out of the housing 13. The central part of the release member 32 is arched over the ears 22 and depending legs are adapted to engage the outer portions of the springs 23 so as to depress the ends of the springs and move them away from the seat in order to unclutch or release the tips or conductors 21.

Instead of having the release member 32 formed with a reduced neck and shoulder for guiding and holding the same in the shell 13, I may provide integral pins 37 on the release member 38, as indicated in Fig. 8, said integral pins playing in slots 39 formed in the 105 sides of the housing 13. This is shown in detail in Figs. 6 and 7.

In Fig. 9 I have shown a modification in which a pair of flat hair pin springs 40 have their bottoms or bends clamped together in 110 parallelism by the integral lugs 41 which are stamped out of the side plates 42 to pinch and hold the bottom of these hair pin springs 40 together. The upper legs of the springs 40 extend diagonally downward toward the seat 20 and are a suitable length to grip the pins or conductors 21 when the same are slid endwise into the seat 20. The lower legs of the springs 40 tend to occupy the dotted line position 115 shown in Fig. 10, but they are of a length which does not permit them to move away from contact with the ends of the pins 21 with the result that these lower legs 43 are merely depressed or put under tension so that 120 when the release member 38 depresses the up- 125

per limbs of the springs 40 to unclutch the pins or conductors 21, the lower limbs 43 resume their normal position and throw the contact pins or conductors 21 out of the sockets 20. To facilitate this action, the outer ends of the lower limbs 43 may have extensions or lugs 45 bent up therefrom to engage the lower ends of the pins 21, and upon release of the upper limbs 40 of these springs, to push the ends of 10 the pins 21 past the ends of the upper limbs of the springs 40 so as to prevent accidental catching of the pins 21 by said upper springs or limbs.

It is believed that the operation of the device is apparent from the foregoing description. The tips 21 are merely pushed into position past the clutching springs and are there held in their seat until the release member is depressed, which release member bends the 20 clutch springs away from the tips and releases the tips. If expulsion springs are used, the tips are automatically expelled when the release member 32 is depressed.

Obviously separate clutch springs and release springs may be employed, if desired.

Now it will be apparent that while I have shown the metal plates 7 and 9 as recurved to form the clutch seat, and this is the preferred manner, it is not necessary that the clutch seat 20 be formed on the metallic plate, such clutch seat may be formed in the shells 14 and 15 as extensions of the openings 30. The spring, such as 23, will make the necessary electrical contact to the plates 7 and 9 and thus to the 25 sleeve 1 and tip 2 of the plug or other contact.

I do not intend to be limited to the details shown and described, except as the same appear in the appended claims.

I claim:—

1. In combination, a terminal comprising a metal plate having a longitudinal seat formed along one edge thereof by bending of the margin of the plate, and a spring arm secured to said plate and extending diagonally toward said seat and having its end disposed adjacent said seat to clutch a conductor which is inserted endwise into the seat, said diagonal spring arm being disposed at such an angle to said seat that movement of the conductor in a given direction will cause the end of the spring to bite more firmly into the surface of the conductor.

2. In combination, a terminal comprising a metal plate having a curved cylindrical portion forming a seat adapted to receive a conductor and a spring arm secured to said plate and extending diagonally toward said seat, said diagonal spring arm being disposed at such an angle to said seat that movement of the conductor in a given direction will cause the end of the spring to bite more firmly into the surface of the conductor.

3. In combination, a terminal comprising a metal plate having a curved cylindrical portion forming a seat for a conductor, a spring

arm secured to said plate and extending diagonally toward said seat, and means for depressing said spring arm to move it away from said seat, said diagonal spring arm being disposed at such an angle to said seat that movement of the conductor in a given direction will cause the end of the spring to bite more firmly into the surface of the conductor.

4. In combination, a terminal comprising a metal plate having its margin bent back upon itself to form a longitudinal seat for a conductor, a spring arm secured to said plate and extending diagonally toward and up to said seat, and means comprising a guiding opening for guiding a pin into said seat, said diagonal spring arm being disposed at such an angle to said seat that movement of the conductor in a given direction will cause the end of the spring to bite more firmly into the surface of the conductor.

5. In combination, a plate having an edge thereof bent around into substantial parallelism to form a seat for a conductor and a leaf spring secured to said plate and having its free end extending diagonally toward and up to said seat, said diagonal spring being disposed at such an angle to said seat that movement of the conductor in a given direction will cause the end of the spring to bite more firmly into the surface of the conductor.

6. In combination, a plate having an edge thereof bent upon itself to form a seat extending longitudinally of said margin, a leaf spring secured to said plate, said leaf spring having its free end extending diagonally toward and disposed at said seat, and guiding means for guiding a conductor endwise into said seat and for limiting lateral movement of said conductor.

7. In combination, a plate having an edge thereof bent about to form a seat for a conductor, a leaf spring secured to said plate and having its free end extending diagonally toward and disposed at said seat, and a shell of insulating material about said seat, said shell having a guiding opening axially in line with said seat.

8. In combination, a shell, a plate having a portion thereof bent to form a substantially cylindrical seat, a leaf spring secured to said plate and having its free end extending diagonally toward and disposed at said seat, and a manually operable release member guided in said shell to engage said spring.

9. In combination, a plate having a portion thereof recurved to form a seat for a conductor, a leaf spring secured to said plate and having its free end extending diagonally toward and up to said seat, a shell about said seat, said shell having a guiding opening axially in line with said seat, and a manual release member of insulation guided in said shell, said release member being adapted to engage said spring to move the end thereof away from said seat.

10. In combination, a plate having an edge thereof recurved to form a seat for a conductor, another edge of said plate being bent over to form a spring seat and a flat spring secured to said spring seat and extending diagonally up to said first seat.

11. In combination, a plate having a margin thereof recurved to form a seat for a conductor, a lug integral with said plate forming spring supporting means, and a flat spring secured to said lug and extending diagonally toward said seat to clutch a conductor in said seat.

12. In combination, a plate having a margin thereof recurved to form a seat for a conductor, a lug integral with said plate forming spring supporting means, and a flat spring secured to said lug and extending diagonally toward said seat to clutch a conductor in said seat, and a release member adapted to engage the spring to bend it away from said seat.

13. A plate having opposite edges thereof recurved to form opposed seats for conductors, a spring secured centrally on said plate, said spring having the free ends thereof extending diagonally towards said opposed seats.

14. In combination, a plate having its opposite edges recurved to form opposing substantially parallel seats, an arched flat spring having its ends extending up to said seats and having its central portion secured to said plate, and means for releasing the ends of said springs by bending the same away from said seats.

15. In combination, a pair of substantially parallel plates, opposite edges of each plate being recurved to form clutch sockets for conductors, an arched spring for each plate having its ends extending diagonally up to the sockets of its plate, the central part of said spring being secured to said plate, and a common release member for depressing all of the ends of the springs simultaneously.

16. In combination, a pair of parallel plates having adjacent edges recurved between said plates to form clutch sockets, leaf springs secured to said plates, each leaf spring having its ends extending up to the sockets diagonally to clutch a conductor therein, and common means for releasing both springs simultaneously.

17. In combination, a pair of parallel plates having downwardly extending lugs, said lugs being inturned to overlie each other, contact means connected to said overlying lugs, said plates having along adjacent margins recurved portions forming clutch sockets, and diagonal springs, one on each plate extending diagonally up to said sockets.

18. In combination, a pair of parallel plates having downwardly extending lugs, said lugs being inturned to overlie each other, contact

means connected to said overlying lugs, said contact means connecting said lugs together, said plates having along adjacent margins recurved portions forming clutch sockets, and diagonal springs, one on each plate extending diagonally up to said sockets, and common means for releasing both springs.

19. In combination, a plurality of plates having laterally extending portions, said portions being arranged to overlap each other, contact means connected to said overlying portions and serving to connect said portions together, said plates having margins thereof formed into clutch sockets, and diagonal springs connected to said plates and extending up to said sockets and means for releasing said springs.

In witness whereof, I hereunto subscribe my name this 5th day of December, 1924.

RILEY M. DIENER.
